United States Patent Office

Des. 216,566

Patented Feb. 10, 1970

216,566

FLASH CUBE HOLDER

Ronnal L. Bewyer, 3600 Manatee Drive SE.,
St. Petersburg, Fla. 33705

Filed Sept. 17, 1968, Ser. No. 13,562

Term of patent 14 years

Int. Cl. D16—07

U.S. Cl. D61—1

Fig. 2

FIGURE 2 is a cross-sectional view at the mid-section of said holder as viewed from the open end thereof, showing the slotted opening for engaging the carrying strap.

I claim:

The design for a flash cube holder, as shown.
